UNITED STATES PATENT OFFICE.

JOSEPH MOSES WARD KITCHEN, OF EAST ORANGE, NEW JERSEY.

BOTTLE-CLOSURE.

1,207,933.

Specification of Letters Patent. Patented Dec. 12, 1916.

Application filed November 28, 1914. Serial No. 874,385.

To all whom it may concern:

Be it known that I, JOSEPH MOSES WARD KITCHEN, a citizen of the United States, residing in the city of East Orange, county of 5 Essex, State of New Jersey, have invented new and useful Improvements in Bottle-Closures, of which the following is a specification.

This invention relates to a device having 10 for its object facilitating the efficient performance of the process of pasteurizing milk in the distributing glass bottle, after the sealing of the bottle. In my copending application, Sr. No. 810,105, filed January 15 3, 1914, which has matured into Patent No. 1,127,778, I am claiming a special form of bottle closure, having advantages for this purpose. The present application claims various improvements in the bottle closure 20 referred to in application Sr. No. 810,105; which improvements, among others, comprise those intended to prevent rusting of the sheet metal used in the construction of the closure cap, to give added strength to 25 that cap, and to prevent the compressible sealing disk of the closure from adhering in the concavity of the cap.

Requirements in a bottle closure suitable 30 for the purpose for which the present invention was devised are desirability, and adaptability to adequately sterilize the bottle's contents and to prevent infection, either directly or indirectly, of the bottle's contents and of the entire mouth and lip of the 35 bottle, including the outer surfaces of the lip.

The several elements comprised in the invention are shown in the accompanying figures, of which—

40 Figure 1 is a plan view of the bottle part of my closure. Fig. 2 is an elevational sectional view of my closure on the line 2—2, Fig. 1. It indicates a sealing disk D, and a labeling disk D³ in close juxtaposition above the sealing disk. Fig. 3 is a longitudinal section of the closure cap on the line 3—3 Fig. 4. Fig. 4 is a side elevation of the metal cap. Fig. 5 is a plan view of the top of the metal cap. Fig. 6 is a side elevation 45 of the glass top of the bottle comprised in my closure. Fig. 7 is a sealing disk I use in my closure. Figs. 8 and 9 are modified forms of the sealing disk. Fig. 10 is an under view of the metal cap, with the sealing disk in place, though not entirely centered over the sealing seat of the bottle lip.

Fig. 11 is a labeling disk. Fig. 12 is a perforated metal disk I use during the process of heating the bottle. Fig. 13 is a section of the perforated disk, taken on the line 13—13 60 of Fig. 12. Fig. 14 is a vertical section of my bottle closure with the perforated disk in place.

Inasmuch as all of the elements of the invention are not used coactively in place 65 at one time, all the elements are not shown in any one of the figures in the accompanying drawings.

Among the reference characters, A represents the bottle closure. 70

B represents the bottle. It may be of any known shape except as to its upper part.

B¹ is an indrawn part of the neck of the bottle B.

C is the metal cap comprising part of the 75 closure.

D is one of the paper sealing disks used in the closure.

D¹ and D² are modified forms of the sealing disk D. 80

D³ is a labeling disk.

The lip L of the bottle has the following construction: It has an internal vertical surface L¹ that is without the usual recessed 85 seat for the commonly used paper board sealing disk. L² is a small curved surface defining the mouth of the bottle. L³ is the annular sealing seat of the bottle. It may be either a flat, horizontal, annular plane, or it may slightly slope downwardly and 90 outwardly from the defined mouth. L⁴ is an outwardly and downwardly curved surface projecting from, and continuous with, the sealing seat L³. It has a curvature having an equal radius and conformation with 95

the curvature C² in the cap C, at or above the level of the top of the lip L. This downward curvature L⁴ is annularly, uniformly, and continuously spaced from the under side of the periphery of the sealing 100 disk D. L⁵ are glass lugs on the lip, the upper level of which is at or below the horizontal line e—e, Fig. 2, at the base of the curvature L⁴. While the upper defining lines of the glass lugs are horizontal, the 105 under defining line of these lugs slope downwardly from the horizontal in one plane. These lugs engage with the centripetally indented lugs C¹ in the skirt portion C² of the metal cap C. It will be observed that in 110 these lugs there is a larger amount of glass at one end of them than at the other end.

This construction is for the purpose of strengthening the lugs at the parts at which the most force is exerted in locking the metal cap C in place. These glass lugs are 5 only two in number, are oppositely placed on the bottle lip, and are each of a length less than one quarter of the inside periphery of the skirt portion of the metal cap C. This opposite placing of, and the limitation 10 of length of these lugs, as well as of the coacting lugs C¹ in the metal cap C, allow for the quick and easy adjustment into place of the metal cap C, prior to the locking of the cap; and for the removal of the cap subsequent 15 to its unlocking. The bellring R has a considerable and unusual projection from the vertical outer side L⁶ of the bottle lip, as also have the glass lugs L⁵. This unusual projection provides for an air containing space A¹ of unusual capacity around 20 the lip of the bottle. The lugs and bellring guide the metal cap to its sealing seat, and the bellring and the skirt portion C⁸ of the cap C, form a conditional seal at the level 25 of the bellring, which protects the lip and other parts inside of the metal cap above the bellring, from insects, dust, and other infecting matters.

The cap C comprises a crown sheet C⁹, an 30 annular skirt portion C⁸, and a connecting annular curved, disk centering surface C². The instruck lugs C¹, lock under the glass lugs L⁵, which locking draws downwardly the crown sheet C⁹ of the metal cap C, comprising 35 the sealing disk D against the sealing seat L³ of the glass lip L. In the descent of the metal cap in its placing, the centering curvature C² of the metal cap laterally shifts the sealing disk D sufficiently 40 to always form a sealed closure with the annular sealing seat L³ of the lip, no matter if the disk is not accurately centered in relation to the sealing seat before the sealing of the closure. Of substantially uniform 45 size, and horizontally disposed with the glass sealing seat L³, is the downstruck compression ring C⁴. Internal to this compression ring are the depressed rings C⁷. These depressed rings C⁴ and C⁷, besides 50 strengthening the metal cap, serve to measurably prevent the sealing disk D from adhering to the under side of the crown sheet C⁹ of the metal cap. On both sides of these 55 depressed rings are upwardly projected cavities C¹⁰ and C¹¹ which help in storing sterilized air under the cap of the bottle.

It will be observed that the surfaces of the centering curvature C² and the skirt portion C⁸ of this cap, are entirely smooth with the 60 exception of the instruck lugs C¹, and have the same radius. This smoothness of surface provides for an easy maintenance of cleanly conditions in the metal cap. The equal curvature formations on the lip and 65 in the cap provide for a conditional seal at

the highest level of the lip, if no compression seal is used.

The two interior depressed rings C⁷ in the cap may be replaced by stamped lettering, or other formations which will help to prevent the sealing disk from adhering to the crown-sheet. Irregular formations of surface, however, in the cap, are not desirable, inasmuch as they tend, whether downstruck or upstruck, to catch and hold infecting 70 matters. Mere annular depressions, such as are herein shown, however, are easily kept 75 clean.

The interior of the cap C, if it is made from a sheet of tin coated steel or iron, as 80 is usually the case, is coated with a special preparation of lacquer, indicated by C¹² Fig. 3, to prevent the rusting of the iron base sheet metal. Non-corrosive sheet metal may be used in making the cap; but such 85 material is expensive. Pin holes or other imperfections in the tin coating of the iron or steel base, afford an opportunity for the rusting of the base metal, with consequent discoloration of the cap and sealing disk. 90 In counteracting the rusting of the cap, the tinned sheet, of which the cap is made, has a coating of the lacquer applied and baked onto the tinned sheet from which the caps are made, before the caps are stamped into 95 shape.

The space A¹ between the vertical exterior sides L⁶ of the glass lip and of the skirt portion C⁸ of the metal cap, along with the concavities C¹⁰ and C¹¹ of the curved centering surface and of the crown sheet of the cap, contain a sufficient amount of air to at least equal in bulk the gases or fluid that may be driven from the bottle during the heating of the bottle's contents; during 105 which heating, the fluid and gases in the bottle expand. When the milk is cooled after its heating, unless there is an absolutely air-tight seal, which is not usually the case, there is a partial vacuum formed 110 in the bottle; and air, under atmospheric pressure, is then forced into the bottle. Inasmuch as during the cooling process, the air outside of the bottle and cap, is cooler than the air under the cap around the warm 115 bottle lip, any air that then goes into the bottle is taken from the sterilized, warmer air underneath the cap; and air that passes the conditional seal at the bellring level, does not reach the upper level seal of the 120 bottle before the partial vacuum in the bottle has been overcome by entrance into the bottle of the sterilized air from the upper levels under the cap. The conditional seal at the level of the bellring, prevents the 125 entrance of substantially all infecting matters into the space A¹, and prevents such matters from coming into contact with the peripheral edges of the sealing disk-gasket. In older forms of bottle closures, the mois- 130

tened edges of the sealing disks, are usually more or less exposed to atmospheric ineffective contact; and these edges being more or less moist, such infections, through reproductive activity of the infecting germs, are conveyed to the interior of the neck of the bottle. The present closure device overcomes that common defect in other bottle closures.

- 10 The sealing disk-gasket D, is preferably made of a more or less compressible material such as wood pulp board. It is of a diameter greater than the outside periphery of the sealing seat L³, and is of a sufficient diameter to extend from the outside periphery of the sealing seat L³ at one edge, to and across the outside periphery of the opposite part of the sealing seat to and touching the centering curvature C² in the 20 cap C. Having this size, no matter what its position may be as to its centering in its emplacement on the bottle lip, the centering curved surface C² centers the sealing gasket sufficiently to effect a perfect closure of the 25 bottle's mouth. The diameter of the disk however, allows of its free dropping from the concavity of the metal cap. The periphery of the sealing disk, extending as it does, over the downward, outward curvature 30 L⁴, enables the person opening the bottle, to remove the disk from the bottle's lip, without infecting manual or instrumental contact with the bottle lip, or with the contents of the bottle. The modified forms of sealing disk, shown in Figs. 8 and 9, provide 35 projecting points D⁷, through whose action, the seal used, may be centered over the bottle mouth, by the centering appositional action of the curvature C² when brought into 40 contact with the contact points. Sealing disks of this form can be made from a lesser amount of paper board stock, than a circular disk such as D. The circular form, however, is to be preferred, because it is 45 more easy to manufacture and pack into rolls, and because it provides a larger surface on which labeling matter may be printed.
- This bottle closure can be used without 50 having a compressible disk gasket interposed between the bottle lip and the compression ring C⁴ of the bottle cap. In that case, there are two conditional seals in the closure, one at the highest level of the 55 bottle's lip, and the other at the level of the bellring. Of course, such seals are not absolutely air-tight, but if the milk is pasteurized in a vertical position in an apartment having a sterilized atmosphere, and the 60 bottle is cooled in the same apartment, there will be no interchange of unsterilized gases between the interior of the bottle and the outside atmosphere after the bottle is removed from the heating and cooling apartment if the bottle is maintained in a sub-
- stantially upright position. It is preferable, however, to use a compressible sealing disk for the high level seal. Sealing disks made from wood pulp are generally used for this purpose, and these are preferably coated with paraffin on both the upper and lower surfaces. All paper material used for such sealing purposes, when subjected to the heat and moisture of the 70 pasteurizing process becomes swollen, distorted, discolored, loses more or less definition of printed matter on it, and is then easily penetrated by moisture. Such moisture during the cooling of the bottle, becomes condensed on the under surface of the 75 crown sheet C⁹, and forms there a layer of water. This water layer acts to cause the sealing disk to adhere "sucker-like" to the crown sheet of the metal cap; and this occurrence necessitates the removal by hand of 80 the adhering disk before the metal cap is re-used. This requirement takes a considerable aggregate amount of time when a very large number of bottles are handled. To 85 overcome this expenditure of time, I, during 90 the heating of the bottle, temporarily place a non-corrosive, perforated disk D⁴, upon the compressible disk gasket D, before I clamp the two disks in place by the aid of a metal cap. The perforated disk D⁴, as is shown 95 in Figs. 12 and 13, has all of its under surface D⁵, smooth and upwardly curved at the edges of the perforations and its peripheral edge, while the upper surface D⁶, is roughened by the upstruck edges of the perforations. The perforated openings allow air to 100 pass between the sealing disk and the perforated disk, and prevent their adhesion. The rough edges of the upstruck perforated metal are restricted to a length that is 105 limited in height to a level below the horizontal crown sheet surface of the metal cap. The peripheral surface of the disk D⁴ is preferably left entirely free from perforations or indentations. Or else, any upstruck 110 indentations in the disk under the lines of the annular compression and spacing rings in the metal cap, are designedly left unperforated in order to prevent scratching of the lacquered surface in the cap. This provision 115 is readily attained by the mere blunting of the points of the perforating prick punches of the stamping die. The perforations are minute in size in order to prevent the swelling upward into them to any considerable 120 extent of any such part of the sealing disk D as would prevent the easy horizontal sliding of the metal cap during its removal from the bottle closure. The overall thickness of the metal disk is preferably not over one 125 sixteenth of an inch. This is a particular feature, inasmuch as the vertical distance between the crown sheet of the metal cap and the locking surfaces of the compression lugs do not allow of any great vertical thick- 130

ness of the perforated disk if the locking closure of the seal is operable. When in place, this perforated disk prevents the sealing disk D in its swelling from coming into contact with the crown sheet of the metal cap; and necessitates that the swelling of the disk be mostly downward. This downward swelling molds the softened disk to the upper parts of the sealing surface L³ of the bottle lip, and in particular, causes the softened paraffined coating of the disk, to adhere to the bottle lip. When the bottle becomes cold, the perforated disk may be easily pushed off horizontally from the sealing disk, its rough upper surface providing for an effective engagement of the tips of the fingers with the disk, and for its sliding removal without breaking the seal between the sealing gasket and the bottle lip.

20 Although there is some slight upward swelling of the sealing disk into the openings of the perforated disk, a very slight revolution of the disk, prior to its sliding removal from the sealing disk, prevents any disturbance of the sealing disk and the sealing seat of the bottle lip. In placing the disks D and D⁴, the two disks are horizontally held between the thumb and fingers of one hand and thus together are equally centered over the sealing surface of the bottle lip when placed thereon. If now, however, the metal cap is clamped into place, it will be found that the paraffined upper side of the sealing disk D has adhesive qualities, which makes its adhesion to the depressed rings C⁴ and C⁷ of the metal cap a possible occurrence. Furthermore, the heating process more or less obliterates printed matter on the sealing disk; and inasmuch as some printed label 40 of an attractive character presenting the dealer's name, the grade of the milk in the bottle, and the day-date of its pasteurization, is a desirable requirement; after the cooling of the bottle, the perforated disk is replaced by a thin labeling disk having on it the necessary printed matter; which labeling disk, is of a character that is devoid of adhesive qualities on its upper side at least. The simplest method of rendering this labeling disk non-adhesive, is to impregnate it with some water resisting material, such as oil or varnish. Inasmuch as the sealing disk remains moist from water absorption, after the cooling of the bottle, it is obvious that some moisture would be absorbed by a dry, porous labeling disk, and thus acquire qualities that would cause it to adhere to the metal cap, the prevention of which occurrence is an important part of the present invention. I do not confine myself to any special method of rendering this supra-cap devoid of adhesive qualities; but impregnation with a water-resisting material is obviously the most available. The adhesion of the paper cap is mostly due to the

presence of watery moisture, although paraffin has considerable adhesive quality. After this labeling disk is in place, the metal cap which preferably should be in a dry condition can be locked, and the milk can then be conveyed for distribution. When the bottle is opened, the two disks will usually be found resting on the bottle lip; and more or less adherent to it; or, if not, they will readily drop from the metal cap by slightly tapping it.

70 This invention comprises the idea of a compressible sealing disk-gasket for the bottle closure, having a moisture-resisting coating on its lower side, such as paraffin, and a coating of a non-adhesive character on its upper side, which non-adhesive coating, in sealing the closure, will come in contact with the crown sheet of the cap without adhering to it while dry and cold.

80 85 Subject matter is herein disclosed that is not herein claimed, but which is claimed in my copending application Sr. No. 810,105, filed January 3, 1914.

Having described my invention, what I 90 claim as new is:

1. In a bottle closure, the coöperating combination of, (1) a glass bottle lip comprising a flat horizontal annular sealing surface, (2) a sheet metal superimposed cap, and (3) a compressible disk gasket compressed between the lip and cap, said superimposed cap comprising a horizontal annular sealing surface, two oppositely placed lugs projecting outwardly from the sides of the lip and a bellring at the lower level of said lip, said cap having a crown-sheet comprising an annular downstruck compression ring of a width of surface substantially the same as the sealing surface of said lip and horizontally disposed on the same plane, and other downstruck projections for spacing the sealing gasket from most of the horizontal surface of the crown sheet, said cap having a coating of heat and moisture resisting lacquer.

100 105 110 115 120 125 130 2. In a bottle closure, the combination with a bottle lip of, (1) means of a soft moldable compressible character for effecting a sealing closure of said lip, (2) means for downwardly compressing to and holding in contact with the top of said lip said first named means, (3) a removable means for temporarily preventing the adhesion of the first and second named means during the heating of said closure, and (4) a non-adhesive paper disk for preventing the adhesion of the first and second named means after the cooling of the heated closure and for indicating the date of the heating of said closure.

3. In a bottle closure, the combination of the following coöperating instrumentalities: (1) a bottle lip, (2) a bell cap superimposed on and covering the entire lip, (3) a com-

- pressible sealing gasket resting on said lip, and (4) a perforated disk resting on said sealing gasket, said disk having a bottom formed in a substantially horizontal plane 5 and being smooth thereon, but being rough on its upper surface and having numerous perforations allowing air to traverse easily through many parts of the disk to all parts of the upper surface of the sealing gasket.
- 10 4. In a bottle closure, the coöperative combination of, (1) a lip, (2) a sealing disk, said sealing disk being coated with a waterproofing material solid at temperatures below 100° F., (3) a metal cap for superimposition above and around the sealing disk during heating of the bottle in the process of pasteurization, and (4) a paper disk of a nonadhesive character superimposed above the first named disk, said combination comprising means for compressing and for holding the two disks in coöperative apposition.
- 15 5. In a bottle closure, the combination of, (1) a lip, (2) a compressible moldable adhesive sealing disk, (3) a bell cap for superimposition on and around the lip, said lip and cap having means for controllably compressing the disk onto the lip, and (4) a non-adhesive paper between the disk and the cap for preventing the adhesion of the disk 20 to the cap.
- 20 6. In a bottle closure, the combination of, (1) a lip, (2) a bell cap having a centering surface, and (3) a sealing disk between the lip and the cap, said disk comprising peripheral projecting contact centering points.
- 25 7. In a bottle closure, the coöperating combination of a cap and a lip, said cap being formed of one stamped piece of sheet metal internally coated over the entire interior with lacquer resisting moisture and repeated pasteurizing heat, having centripetally indented lugs on the skirt portion of the
- cap, said lip comprising projecting glass lugs for coöperation with the indented lugs in the cap, said lugs compressing together and holding in place the cap and the lip.
8. In a bottle closure, the combination of the following coöperating instrumentalities, (1) a bottle lip comprising a horizontal sealing seat, and a conditional seal at a lower level of the lip, (2) a compressible sealing disk for the sealing seat, (3) a non-corrosive perforated metal disk for superimposition above the compressible sealing disk, (4) a secondary sealing disk resistant to moisture 50 for superimposition over the first named disk, and (5) a metallic supra-cap covering the said seals and the said lip, said cap having means for acting in coöperation with said lip for compressing said seal against said lip, said cap comprising means for applying the sealing pressure exclusively over the sealing surface of said lip, said cap comprising means for partially preventing adhesion of the second named sealing disk to 55 said metallic cap.
9. In a bottle closure, the combination of, (1) a lip having an upper level sealing surface and a bellring conditional sealing surface, (2) a superimposed bell cap having a sealing surface for compression against said upper sealing surface of said lip and a skirt portion for securing a conditional seal with the bellring, (3) a compressible moldable sealing material for forming an air-tight 60 seal at the upper level of the lip, and (4) a paper disk resisting watery moisture between the sealing material and the cap for preventing adhesion between the sealing material and the cap.
